HAND OPERATED TRAFFIC LINE PAINTING
BRUSHJohn Bailey Pridgen and Howard Brown Wentz,
Charlotte, N. C.Application December 12, 1931
Serial No. 580,692

2 Claims. (Cl. 91—39)

The object of our invention is to provide a hand operated traffic line painting brush that can be used successfully to paint short lines in close places where a large traffic line painting brush machine cannot be advantageously operated.

We attain these and other objects of our invention by the device illustrated in the accompanying drawing, in which,—

Figure 1 is a perspective view of our invention;

Fig. 2 is a longitudinal section through the back of our brush, the handle and paint delivery pipe being shown in side elevation, a portion of the handle, however, being broken away to show the mounting of the paint delivery brush in

same; and

Fig. 3 is a vertical transverse section through our paint brush.

Like numerals designate like parts in each of the several views.

Referring to the accompanying drawing, we provide a brush 1 having an opening or chamber in the center of the brush back and having front and back rows of bristles forming the brushes 3, as shown in Fig. 2. These brushes 25 3 are preferably wire brushes, or spaced rows of bristles with an intervening strip of folded asbestos or other material folded into a close U shape.

Mounted on each of the sides of the brush back are two metal strips or blades 4, as shown in Fig. 3, which are provided with vertical slots 8 through which are inserted bolts 5 having nuts 6 and washers 7 to permit of a free vertical movement of the blades as the brush is moved along 30 35 on the roadway or street.

We provide leaf springs 9 mounted by means of suitable brackets 10 on the brush back 1 and having the free ends of the leaf springs resiliently engaging the upper edge of the metal blades 4, as 40 best shown in Fig. 1. We provide a metal strap 11 fastened to the hollow handle 17 and to the brush back 1 by a bolt or screw 12. We also provide metal straps 13 secured to the metal handle 17 by suitable rivets 14 and to a fastening plate 45 16 by a pin or bolt 15, a plate 16 in turn being suitably affixed to the front portion of the brush back 1, as shown in Fig. 2. Hollow handle 17 is provided with a removable cap 18 to permit of filling the hollow handle with suitable paint. 50 Mounted on the hollow handle 17 we provide an operating lever 19 rotatably mounted in the eyes 20 and having an offset handle 21 functioning as a handle element and positioned near the upper end of the hollow handle 17. Lever 19 is 55 provided with an offset lower end 22 attached to

the arm 23 of valve 24 which valve is adapted to open and close the passage through the delivery pipe 25 to start or stop the flow of paint through said pipe into the open chamber 2 between the rows of bristles 3. The paint delivery pipe 25 is 60 preferably flared at its lower end, as shown in Fig. 3.

In operation the cap 18 of hollow handle 17 is removed to permit of filling the hollow handle 65 with paint. The valve 24 in paint delivery pipe 25 is opened by operating the handle portion 21 of lever 19 which is operatively connected with the valve, diagrammatically shown at 24, and which may be any suitable valve. The paint flows onto the roadway or street and is spread 70 by the brushes 3 while it is prevented from flowing out laterally to any extent by the blades 4 which automatically adjust themselves to the contour of the roadway as they are loosely mounted for vertical sliding movement by means 75 of the slots 8 and the bolts 5 through said slots. The metal blades or sides 4 function as runners and to some extent support the brush, no wheels being necessary.

What we claim is:

1. In a hand operated traffic line painting brush, the combination of a brush back having an opening in the central portion to permit paint to flow therethrough, a plurality of spaced sets of brushes affixed to the back, one of said brushes being positioned in front of and spaced from the other the front brush functioning as a sweeper and the rear brush as a painting brush, metal side strips loosely mounted on the back to permit of automatic adjustment of same on the road 80 bed, leaf springs rigidly attached to the back and having their free ends resiliently engaging the top of the metal side strips, a hollow handle rigidly affixed to the back and adapted to contain paint, and means for the delivery of paint 85 from the hollow handle to the open chamber in the center of the brush back.

2. In a hand operated traffic line painting brush, the combination of a brush back having an opening in the central portion to permit paint to flow therethrough, a plurality of spaced sets of brushes affixed to the back, leaf springs rigidly attached at their central portions to the back and having their free ends resiliently engaging the top of the metal side strips, the said metal side strips, and a valve controlled paint delivery pipe.
